UNITED STATES PATENT OFFICE.

TIMOTHY J. SHEA AND RICHARD HAMES, OF SHELTON, CONNECTICUT.

COMBINATION BED AND PARLOR SUIT.

988,513.

Specification of Letters Patent.

Patented Apr. 4, 1911.

Application filed October 27, 1910. Serial No. 589,478.

To all whom it may concern:

Be it known that we, TIMOTHY J. SHEA and RICHARD HAMES, citizens of the United States, residing at Shelton, county of Fairfield, State of Connecticut, have invented an Improvement in Combination Beds and Parlor Suits, of which the following is a specification.

This invention has for its object to provide a combination bed and parlor suit adapted for general use and especially adapted for use in restricted quarters, as in city apartments and in bungalows, which shall consist simply of two divans and two chairs, said members of the suit being provided with means for quickly and securely attaching them together to form a bed and as quickly detaching them again, the backs of the chairs being detachable and the divans being provided with drawers to receive the chair backs and the bed clothing.

With these and other objects in view we have devised the simple and novel combination furniture suit of which the following description in connection with the accompanying drawings is a specification, reference characters being used to indicate the several parts:

Figure 1 is a perspective of one of the divans detached as in use; Fig. 2 a perspective of a chair detached and ready for use; Fig. 3 a perspective showing the four members of the suit attached together and forming a bed; and Fig. 4 is an enlarged detail view illustrating the means for attaching the members together.

A denotes divans and B chairs. The divans are used without change, the backs, indicated specifically by 10, comprising when assembled to form a bed the head and foot-board, respectively, of the bed, it being wholly unimportant in which relative position either divan is placed. The backs of the chairs, indicated specifically by 11, are easily detachable. Each divan is provided with a drawer 12 which may open from either front or rear, as preferred, said drawers being adapted to receive the chair backs when the members are assembled to form a bed and to receive the bed clothing when the members are disassembled as when in use as a parlor suit.

13 denotes the seats of the divans and 14 the seats of the chairs, which are preferably upholstered relatively flat, as shown in the drawings.

It is wholly unimportant so far as the principle of the invention is concerned just how the frames of the divans and chairs are constructed. They may be made of either metal or wood and of as high grade as may be required, it being an important feature of the invention that there are no unsightly parts and that the invention is equally adapted to either high priced or low priced furniture. We have shown the members of the suit as having metal frames to which casters 15 are attached in any ordinary or preferred manner.

16 denotes the front legs of the divans and 17 the back legs of the chairs. The attachment of the members together is effected by means of rotary collars 18 provided with eyes 19 on the front legs 16 of the divan and rotary collars 20 provided with eyes 21 on the back legs of the chairs. One collar only is used on each front divan leg, and two collars, each having an eye and connected by a brace 22, are used on the back chair legs. The legs are provided with pins 23 on opposite sides, the pins on one side only being shown, and the collars are provided with notches 24 which engage the pins and retain the collars in the locking or unlocking position.

In locking the members together for use as a bed, the collars on the contiguous divan and chair legs are turned toward each other as in Figs. 1 and 4, placing the eyes in alinement, the eye on the divan leg lying intermediate the eyes on the chair leg. When in this position a locking pin 25 is passed through the eyes as in Fig. 4, the head of the pin resting upon the upper eye. The locking pins are attached to chains 26, the other ends of which are permanently attached to the sides of the divan frame, as at 27 (see Figs. 1 and 3). When not in use, the collars 18 on the divan legs are turned backward out of the way and locked there by engagement of the collars with pins 23 and the locking pins are disposed of by placing them in the eyes, as clearly shown in Fig. 1. The locking collars 20 on the chair legs and their eyes have the additional function of securing the backs 11 to the chairs when in use as such, as in Fig. 2. Each chair back is provided with downwardly extending rods 28 adapted to engage the eyes 21 of collars 20 on the back chair legs, as in Fig. 2. To assemble the members to form a bed, it is therefore simply necessary to re-

move the chair backs which may be placed in the drawers in the divans, place the chairs with the back legs outward between the divans, turn the respective collars on the front legs of the divans and the back legs of the chairs to the position shown in Figs. 3 and 4, and lock the members together by passing the locking pins through the aligned eyes on the members. To disassemble the members and provide a parlor suit, the locking pins are withdrawn, the collars on the divan legs are turned to the position shown in Fig. 1, the locking pins being preferably placed therein for retention, the collars on the chair legs are turned to the position shown in Fig. 2 and the downwardly extending rods 28 at the lower ends of the chair backs are placed in engagement therewith, as clearly shown, which leaves the chairs ready for use.

Having thus described our invention we claim:

1. The combination of two divans having permanent backs, two chairs having removable backs provided with depending rods, the united depth of said chairs being equal to the width of said divans, supporting devices carried by the back legs of said chairs

to receive said rods to support said backs, and fastening means carried by the front legs of said divans and adapted to coöperate with said supporting devices to unite the divans and chairs when the backs of the latter are removed, whereby a bed is formed.

2. The combination of two divans having permanent backs, two chairs having removable backs provided with depending rods, the united depth of said chairs being equal to the width of said divans, shiftable supporting devices carried by the back legs of said chairs to receive said rods when in one position to support said backs, and fastening means carried by the front legs of said divans and adapted to coöperate with said supporting devices when in their shifted position to unite said divans and chairs when the backs of the latter are removed, whereby a bed is formed.

In testimony whereof we affix our signatures in presence of two witnesses.

TIMOTHY J. SHEA.
RICHARD HAMES.
